[57] CLAIM

The ornamental design for a colored telephone address leaf, as shown and described.

DESCRIPTION

FIG. 1 is a front elevational view of a colored telephone address leaf showing our new design; and,

FIG. 2 is a rear elevational view thereof.

The colored telephone address leaf is flat and of conventional thickness.

The drawing is lined, in part, for the color yellow and for two different shades of blue, the darker shade of blue being lined more densely than the lighter shade of blue.
